Primary Examiner — Karen E Eldridge Powers*(74) Attorney, Agent, or Firm* — Benesch, Friedlander, Coplan & Aronoff LLP(57) CLAIM

The ornamental design for a handle for a cosmetic brush, as shown and described.

DESCRIPTION

FIG. 1 is a front elevational view of a handle for a cosmetic brush, showing the design.

FIG. 2 is a side elevational view of the handle for a cosmetic brush.

FIG. 3 is a rear elevational view of the handle for a cosmetic brush, taken at an angle to one side.

FIG. 4 is a top view of the handle for a cosmetic brush; and, FIG. 5 is bottom view of the handle for a cosmetic brush. The broken lines shown near the top of FIGS. 1, 2 and 3, and at the periphery of FIGS. 4 and 5, illustrate portions of the article that form no part of the claimed design.

The broken line shown at the center of FIG. 4 illustrates a boundary of the claimed design and forms no part thereof.
